UNITED STATES PATENT OFFICE.

WILLIAM G. LATIMER, OF DETROIT, MICHIGAN, ASSIGNOR TO THE LATIMER CASH REGISTER COMPANY, OF SAME PLACE.

CASH-REGISTER.

SPECIFICATION forming part of Letters Patent No. 448,245, dated March 17, 1891.

Application filed April 19, 1890. Serial No. 348,742. (No model.)

To all whom it may concern:

Be it known that I, WILLIAM G. LATIMER, a citizen of the United States, residing at Detroit, in the county of Wayne and State of Michigan, have invented certain new and useful Improvements in Cash-Registers, of which the following is a specification, reference being had therein to the accompanying drawings.

10 This invention relates to new and useful improvements in cash-registers; and the invention consists in the peculiar construction of a device for preventing the simultaneous operation of two or more keys.

15 This invention is intended to form an improvement upon my United States Letters Patent No. 409,107, dated August 13, 1889.

In the drawings, Figure 1 is a vertical section through a cash-register, showing my invention in elevation. Fig. 2 is an enlarged view showing my invention in section. Fig. 3 is a plan view of the devices shown in Fig. 2. Fig. 4 is a vertical cross-section at right angles to that shown in Fig. 2 on line $x-x$, Fig. 1; and Fig. 5 is a detail.

20 Are the keys grouped in banks of nine, pivoted upon the transverse shaft C, and each carrying at its rear end the tablet-rods D and registering-rods E, the latter operating the 25 registering-wheels F through the medium of the swinging rack-bar G.

H is a swinging bar engaging under the shoulder H', which bar is moved out during a limited period by the arm I, moved by the 35 knocker I', all of known construction.

a is a cross-bar, having either an inclined lower edge or having a step b above each key-lever, so arranged that the operation of each key will raise the cross-bar a different distance. This bar at its ends engages in vertical guides c.

d is a quick-threaded screw secured centrally upon the top of the cross-bar a. This screw passes through a central aperture in the disk e, which is pivotally supported in the bar f of the frame. The relative movements of the screw and key are governed by the extent of the step on the bar a, and the rotation of the disk is governed by the relative vertical movement of the screw and the pitch of the thread thereon.

g is a bar slidingly secured to the under side of the disk in the guides h, and having head i apertured to embrace the screw and of sufficient size to allow a slight lateral movement of the arm upon the screw. This head has a semicircular screw-threaded bearing j upon one side. This bearing is held in engagement with the screw by the spring k. The disk e has an aperture l near its edge, 60 the free end of the bar g extending partially across this aperture.

m, Fig. 3, is a spiral spring secured at one end to the bar f and at the other end to the flange n on the disk e.

o is an abutment on the disk, adapted to strike the stop o' and hold the disk in against further rotation by the tension of the spring.

p are a series of curved arms on the keys, arranged beneath the disk and in the path of the aperture l.

The parts being thus constructed and arranged, they are intended to operate as follows: Upon the operation of a key—say the middle key, as shown in Fig. 2—the key rises 75 a short distance before striking the bearing b of the cross-bar a. When it strikes the cross-bar, it raises it and with it the screw d. The engagement of the screw with the screw-threaded bearing j of the bar g, which is carried by the disk, causes the disk to rotate until the end of the lever g is opposite the upper end of the pin p upon this lever. The further upward movement of the key bears against the end of the bar g, moving it inward and disengaging the bar g from the screw, thus stopping further actuation of the disk. The aperture l in the disk is thus stopped opposite the pin, which enters the aperture in its farther upward movement, locking the disk from further movement. The disk having but one aperture, it is evident that but one key can be operated at a time.

If two or more keys are operated, the pin upon but one can enter the aperture in the disk. 90 The others would strike the imperforate portion of the disk. When the key is lowered, the spring m returns the disk to the normal position, and the spring k likewise returns the arm g to its normal position.

100 What I claim as my invention is—

1. In a cash-register, the combination, with

the keys, of a series of arms carried thereby, a movable disk having an aperture, and connecting mechanism adapted to move the disk, bringing said aperture in position to register with the arm on an operated key, substantially as described.

2. In a cash-register, the combination, with the keys, of a series of arms carried thereby, a rotating disk having a single aperture, and connecting mechanism adapted to rotate said disk to bring the aperture to register with the arm on an operated key, substantially as described.

3. In a cash-register, the combination, with the keys, of a series of arms carried thereby, a cross-bar adapted to be moved a different distance by each key, a screw on said cross-bar, a disk rotated by said screw, and an aperture in said disk, adapted to register with the arm of an operated key, substantially as described.

4. In a cash-register, the combination, with the keys, of a series of arms carried thereby, a cross-bar adapted to be moved a different distance by each key, a screw on said cross-bar, and a disk rotated by said screw through the medium of the arm *g*, adapted to be detached from said screw when the aperture in the disk registers with the arm upon an operated key, substantially as described.

5. In a cash-register, the combination, with the keys, of a series of arms carried thereby, the cross-bar *a*, having shoulders *b* of different heights, guides *c*, screw *d*, disk *e*, arm *g*, spring *h*, bearing *j*, aperture *l*, and spring *m*, substantially as described.

In testimony whereof I affix my signature in presence of two witnesses.

WILLIAM G. LATIMER.
